UNITED STATES PATENT OFFICE

146,522

DESIGN FOR A MERCHANTISE SHOWCASE OR THE LIKE

Paul M. Ressinger, Chicago, Ill.

Application July 28, 1945, Serial No. 121,033

Term of patent 14 years

(Cl. D80—11)

To all whom it may concern:

Be it known that I, Paul M. Ressinger, a citizen of the United States, residing at Chicago, in the county of Cook and State of Illinois, have invented a new, original, and ornamental Design for a Merchandise Showcase or the like, of which the following is a specification, reference being had to the accompanying drawing, forming part thereof.

The figure is a perspective view of a merchandise showcase showing my new design.

The rear of the cabinet not readily visible from the front is plain.

I claim:

The ornamental design for a merchandise

showcase or the like, substantially as shown and described.

PAUL M. RESSINGER.
